UNITED STATES PATENT OFFICE.

CARL C. KRUEGER, OF SAN ANTONIO, TEXAS, ASSIGNOR TO SAN ANTONIO MACHINE & SUPPLY CO., OF SAN ANTONIO, TEXAS, A CORPORATION OF TEXAS.

AUTOMATIC COTTON PACKER.

Application filed March 19, 1924. Serial No. 700,289.

To all whom it may concern:

Be it known that I, CARL C. KRUEGER, a citizen of the United States, residing at San Antonio, in the county of Bexar and State of Texas, have invented certain new and useful Improvements in Automatic Cotton Packers, of which the following is a specification, reference being had to the accompanying drawings.

10 This invention relates to automatic cotton packers of the character disclosed in the patent granted to George W. Cameron, Patent #1,188,894, granted on the 27th day of June, 1916.

15 One of the objects of the present invention is to provide means for automatically braking the feeder which feeds the cotton into the packing box and beneath the plunger or ram.

20 A further object is to provide means for automatically shifting the belt which operates this feeding mechanism so that when the brake is applied to the pulley which drives this feeding mechanism the belt will be shifted away from the pulley and when the brake is removed the belt will be shifted into operative engagement with the pulley.

25 A further object is to provide a construction of this character in which the braking action is automatic and controlled by the plunger or ram of the packer whereby said belt shifting and automatic braking action is caused to occur intermittently.

30 A further object is to provide a construction of this character which is very simple, may be readily applied and will not be liable to get out of order.

35 Other objects will appear in the course of the following description.

40 My invention is illustrated in the accompanying drawings wherein:

Figure 1 is a fragmentary top plan view of a cotton trumper having my improved automatic belt shifting and braking mechanism applied thereto;

Figure 2 is a fragmentary front elevation of the construction shown in Figure 1;

Figure 3 is a sectional view through the fast and loose pulleys to show the brake shoe in section;

Figure 4 is a section on the line 4—4 of

Figure 1, the feeding mechanism being shown in elevation;

Figure 5 is a fragmentary front elevation of the controlling mechanism;

55

Figure 6 is a fragmentary top plan view of the link 21 and its pivoted support 22.

Referring to these drawings, A and B designate the longitudinal beams of longitudinal supporting sills of a cotton packer, 60 these sills being parallel to each other but spaced from each other by suitable transverse braces. These sills are supported by vertical members C and D and mounted upon the vertical members D is the feeding 65 hopper E of the cotton packer. This hopper feeds into the packer box F of the packer in any ordinary or usual manner and at this end there is a feeding roll 10 disposed within the hopper E, the shaft of 70 which extends out through the ends of the hopper, one end of the shaft carrying upon it the sprocket wheel 11. Mounted upon an upright G forming part of the frame of the machine is a drive shaft 12 carrying a sprocket wheel 13 and over this sprocket wheel passes a sprocket chain 14 which extends around the sprocket wheel 11, thus 75

the sprocket wheel 11 and the feeding roller are driven from the shaft 12. Mounted upon the shaft 12 is a fast pulley 15 and disposed also upon this shaft and immediately adjacent the pulley 15 is a loose pulley 16. Passing either over the pulley 15 of the loose pulley 16 is a belt 17 which 80 extends downward from a power shaft mounted in any suitable manner, this shaft not being shown.

85 Mounted in bearings 18 on the under faces of the longitudinal beams A and B is a 90 rock shaft 19 which carries the upwardly extending arm 20 adjacent one end and to which is pivoted the link 21. This link at its opposite end extends into a position contiguous to the vertically movable plunger 95 and plunger guide of the trumper and is pivoted to a lever 22 which extends downward and away from the link 21 and is pivotally connected, as at 23, to the plate 24. The link 21 at its end which is pivoted 100 to the lever 22 is formed to provide a stirrup bend 25 and in this stirrup a roller 26

is supported, this roller being disposed in such position as to be engaged by a vertically movable finger 27 bolted to the foot of the guide post 28 which guides the 5 plunger or ram. On the upward movement of the plunger the beveled end of the finger 27 is forced against the roller 26 causing an upward and inward movement of the roller and of the rod 21, thus causing an 10 oscillation of the rock shaft 19 in one direction.

Attached to the upper extremity of the arm 20 is a contractile spring 29 which tends to pull this arm 20 over toward the left in 15 Figure 5. The extremity of the rock shaft 19 remote from the contractile spring 29 is angularly bent, as at 30, so that this angular arm so formed extends upward and outward. Operatively connected to the extremity of 20 this angular arm is a longitudinally shift- 25 able rod 31, whose end remote from the ex- tremity of the arm 20 is shiftably mounted in a bracket 32 mounted upon the adjacent post C. Thus as the rock shaft 19 is os- 30 cillated in one direction or the other the rod 31 will be longitudinally shifted in one direction or the other. This rod 31 carries upon it the two upwardly extending spaced belt shifting fingers 33 which engage the 35 belt 17. When the rod 31 is shifted in one direction the belt will be shifted onto the loose pulley and when shifted in a reverse direction the belt will be carried onto the fixed pulley.

35 Mounted in bearings upon the upper faces of the sills A and B is a transverse rock shaft 34 which carries intermediate its ends the downwardly extending arm 35 which is pivotally connected to a link 36 which in turn 40 is connected to an upwardly extending arm 37 mounted upon the rock shaft 19. Thus as the rock shaft 19 is oscillated the rock shaft 34 will be oscillated. This rock shaft carries upon it and operatively connected to 45 it the brake shoe 38 which is adapted to be applied to the fixed pulley 15. In other words, when the rock shaft 34 is oscillated in one direction the brake will be applied to the fixed pulley and when it is oscillated in 50 the other direction the brake will be relieved from the fixed pulley. The lower extremity of the arm 35 has attached thereto one end of a contractile spring 39, the other end of 55 which is attached to any suitable point of support as, for instance, one of the trans- 60 verse beams, and this spring acts to urge the rock shaft into a direction which will carry the brake shoe against the face of the pulley.

65 The operation of this invention is as fol- 60 lows: While the cotton is being fed into the press box before the plunger is lowered, the belt 17 is engaged with the fast pulley 15. Under these circumstances, of course, the plunger is raised as well as the plunger 65 guide and as a consequence the beveled end

of the finger 27 has borne against the roller 26 and forced the link 21 over toward the right. This carries the arm 30 over toward the right but shifts the rod 31 so that the fingers 33 carry the belt in engagement with the fixed pulley 15, thus driving the feeding mechanism through the shaft 12 and the sprocket chain 14. As soon as the plunger moves downward, however, and the finger 27 has released the roller 26, the springs 29 and 39 act to oscillate the shaft 19 to the left and shaft 34 to the right. This movement of the shaft 19 acts to shift the rod 31 so as to carry the fingers toward the left in Figure 1 and shift the belt 17 from the tight to the loose pulley and at the same time the oscillation of the shaft 34 applies the brake shoe to the fast pulley, stopping the feeding mechanism immediately so that no cotton is fed from the hopper into the press box 85 while the plunger is descending. The parts will remain in this position until the plunger again ascends, whereupon the beveled end of the finger 27 engages the roller 26, shifts the arm 21 to the right and again applies the 90 belt to the fast pulley and releases the brake and thus causes the driving of the feeding mechanism. It will be seen that this shifting of the belt and of the brake is automatic in its action and is entirely produced by the 95 intermittent up and down movement of the packing plunger. Thus the belt shifting and braking action is entirely under control of the plunger or ram of the packer and occurs intermittently whenever the packing 100 plunger rises or lowers. While I have illustrated certain details of construction and arrangement of parts which are particularly designed for use with the Cameron packer, forming the subject-matter of Patent 105 #1,188,894, I do not wish to be limited thereto as it is obvious that many changes might be made in these details of construction and the arrangement of parts in order to fit the mechanism to other cotton packers 110 without departing from the spirit of the invention as set forth in the appended claims.

I claim:

1. A device of the character described comprising a reciprocatable plunger, a rotatable feeding member delivering in advance of the thrust of the plunger, means for driving the feeding member including fast and loose pulleys, a driving belt for the fast and loose pulleys, an oscillating belt shifter operatively engaged with the belt, a brake movable toward and from the fast pulley, and means operated by a predetermined ascent of the plunger acting to shift the belt from the loose to the fast pulley and release the brake and upon a predetermined descent of the plunger acting to shift the belt to the loose pulley and apply the brake.

2. A device of the character described

comprising a reciprocatable plunger, a rotatable feeding member delivering in advance of the thrust of the plunger, means for driving the feeding member including a shaft,

- 5 fast and loose pulleys mounted upon the shaft and a belt coacting therewith, a rock shaft, a brake shoe operatively connected to the rock shaft and coacting with the fast pulley, a longitudinally shiftable belt shifting rod having belt shifting fingers engaging the belt, the rock shaft being operatively connected to the shifting rod to cause a reciprocation of the shifting rod in a direction to carry the belt from the fast to the loose pulley upon a rocking motion of the rock shaft to release the brake, means yieldingly holding the rock shaft in position to apply the brake, and means operatively connected to and vertically reciprocable with the

20 plunger for rocking the shaft in a direction to release the brake and cause a movement of the shifting rod to a position to apply the belt.

3. A device of the character described

- 25 comprising a reciprocating plunger, a rotatable feeding member delivering in advance of the thrust of the plunger, means for driving the feeding member including a shaft, fast and loose pulleys mounted upon the shaft, a belt coacting with the plunger, a rock shaft extending at right angles to the axis of the first named shaft, a brake shoe operatively carried by the rock shaft and adapted to engage the fast pulley, the rock shaft at its extremity being angularly bent, a longitudinally reciprocatable rod operatively connected at one end to the angular end of the rock shaft and reciprocatable thereby, belt engaging fingers mounted upon the rod, a second rock shaft, a brake shoe carried thereby, operative connections between the first and second rock shafts whereby they may simultaneously oscillate, a member vertically movable with the plunger and having a beveled extremity, an arm on the first named rock shaft, a link operatively pivoted to said arm, means engageable by the upper end of the beveled extremity whereby the link may be drawn in one direction to cause the oscillation of the rock shaft in the same direction, the release of said brake and the shifting of the belt to the fast pulley upon an upward movement of the plunger, and springs resisting an oscillation of the rock shafts and urging the rock shafts to a position where the brake is unapplied and the belt is shifted onto the loose pulley.

4. A device of the character described comprising a reciprocating plunger, a feeding member delivering in advance of the thrust of the plunger and means for driving the feeding member including a shaft, fast and loose pulleys applied thereto and a belt coacting therewith, a rock shaft extending transversely to the pulley shaft and having

arms at its opposite ends, a link connected to one of said arms and extending toward the plunger and having a yoke mounted upon the end of the link, a member operatively mounted upon and coacting with the plunger and moving vertically therewith, the member having a beveled end engaging said yoke to cause the oscillation of the rock shaft in one direction, a spring causing the oscillation of the rock shaft in the opposite direction, a longitudinally shiftable shifter rod operatively connected to the other of said arms of said rock shaft and carrying belt shifting fingers, a second rock shaft, a brake shoe carried thereby and engageable with the fast pulley, and an arm mounted on the second rock shaft and operatively connected to the first named rock shaft to rock therewith.

5. A device of the character described comprising a reciprocating plunger, a feeding member delivering in advance of the thrust of the plunger, a driving shaft therefor having fast and loose pulleys mounted thereon and a belt coacting with the fast and loose pulleys, a rock shaft extending transversely of the driving shaft and having radially extending arms on its opposite ends, a link pivotally connected to one of said arms and extending toward the plunger and angularly bent at its end to form a roller supporting yoke, a member mounted upon the plunger rod and having an inclined upper end adapted to engage said roller, a lever adjacent the plunger pivotally supported at one end and at its other end pivotally engaged with said link, a spring engaged with one of the arms and urging the rock shaft in a direction to carry the yoke away from the plunger, a slidingly mounted shifter rod operatively connected to the other of said arms and reciprocated thereby and having a pair of belt-engaging fingers, a second rock shaft extending parallel to the first named rock shaft and having a depending arm, an arm on the first named rock shaft, a link connecting the two arms, and a brake shoe mounted on the second named rock shaft and engaging the fast pulley.

6. A device of the character described including a plunger, a hopper discharging in advance of the plunger, a feeding roller mounted within the hopper, a driving shaft therefor operatively geared thereto and mounted upon the frame, said shaft extending parallel to the frame, fast and loose pulleys mounted upon the shaft, a belt coacting therewith, means for shifting the belt from the fast pulley to the loose pulley upon the downward movement of the plunger and from the loose pulley to the fast pulley upon the upward movement of the plunger comprising a transverse rock shaft having an arm, a lever pivotally mounted at one end and disposed adjacent the plunger, a link

pivoted at one end to said lever and at its other end to said arm and having a roller supporting yoke, a member movable with the plunger and having a beveled upper end ¹⁰ adapted to engage the roller of the yoke to shift the link in one direction to thereby oscillate the shaft, belt shifting means operatively connected to said transverse shaft,

a brake, brake operated means operatively supporting the brake in position opposite the fast pulley, and means operatively connecting said brake operating means with said rock shaft.

In testimony whereof I hereunto affix my signature.

CARL C. KRUEGER.
